JOSEF KÖHLEN, OF HERNE, GERMANY.

ROCK DRILL.

Application filed January 20, 1923, Serial No. 613,889, and in France November 17, 1922.

My present invention relates to rock drills and more particularly to pneumatic rock drills with reciprocating valves, i. e. valves whose reciprocating valve body may have 5 the shape of a ball, a flap, a poppet, or of any other convenient configuration adapted to direct the motive fluid alternately to both faces of the reciprocating piston. In rock drills of this kind it frequently happens that 10 the reciprocating piston does not attain its full stroke, because leakages between the valve and the valve seat permit the motive fluid to continue to flow into the cylinder when theoretically the admission of the motive fluid should have ceased, for which reason 15 the counteracting compression sets in too early. The result of this incorrect action is that the stroke of the piston, and in consequence thereof that of the percussion 20 bar attached thereto, is shortened to an undesirable extent. Now then, since the percussion bar is utilized in a well-known manner as a means to impart after each blow a certain amount of partial rotation to the 25 drill in order to effectively bring the drill into operative position for the next blow, this partial rotation of the drill must likewise of necessity fall short of the required extent when the piston stroke is unduly 30 shortened. The final result of these shortcomings is that the drill gets jammed up in the bore hole and thus becomes inoperative. My present invention avoids these drawbacks by means of small by-pass channels 35 arranged in the cylinder wall in the direction of the piston travel. These by-pass channels are made to cooperate with annular channels cut into the periphery of the piston and thus connect the cylinder chambers 40 again with their exhaust ports after the latter have been fully shut off from their cylinder chambers preparatory to the compression. This after-exhaust of spent motive fluid from said cylinder chambers, on 45 account of the full length of the piston stroke secured hereby, increases not only the percussive force of the percussion bar but also assures a jerkless operation of the rock drill, because the formation of the air-cushion for braking purposes previous to the reversal of the piston is now executed more regularly than formerly and is accomplished in full accordance with the true adiabatic curve. 50 It is, however, necessary that the diameter of the by-pass channels employed to obtain a satisfactory after-exhaust be not too large in order to avoid the loss of too much live motive fluid, because during the admission of live motive fluid to the reversed 60 piston these by-pass channels connect the cylinder chambers for a second time with the exhaust ports, so that a loss of live motive fluid, however small, is unavoidable. Although the exhaust ports are hereby 65 opened for an instant only, since at this moment the piston has already attained its highest velocity, the length of these by-pass channels must nevertheless be such that the 70 exhaust of live motive fluid does not annul the advantage secured by a sufficiently extended after-exhaust. In the accompanying drawing the invention is illustrated as applied to a pneumatic rock drill Fig. 1 being a longitudinal section, and Fig. 2 a cross section. 75 In the cylinder 1 of the rock drill shown, a reciprocating working piston 2 is arranged with which a percussion bar 3 is preferably integrally connected. The motions of piston and percussion bar are controlled by a reciprocating ball-valve 4, which on account of the reduction of the cylinder pressure, caused by the exhaust, alternately 80 engages and leaves the valve seats 5 and 6 85 in the well known manner. The opening in the seat 5 communicates with the circular cylinder chamber 7, whereas the opening in the seat 6 is similarly connected with the annular cylinder chamber 8. The motive 90 fluid, in this case compressed air, is admitted to said ball-valve 4 through perforations 9 arranged in the wall of the valve-chamber 4'. The cylinder 1 is closed at the top by a handled cylinder cover 10 and at the bottom by means of a casing 11. The latter 95 guides the percussion bar 3 and contains a sleeve 12 which in connection with a tool holder 13 and ratchet mechanism of well-known character, such as shown in Fig. 2 100 imparts to the drill—not shown in the drill socket 13—during the return stroke of piston and percussion bar a partial rotation, required to enable the cutting edges of the drill to chip off new particles of stone at the 105 bottom of the bore-hole at the next blow of the percussion bar on the drill. To this end the percussion bar 3 is provided with helical grooves 14 which at their lower end merge into straight transmitting channels 110 15. The sleeve 12 engages the channels 14 by means of tongues 12' and in a similar

manner the tool holder 13 engages the channels 15 with tongues 13''. When the piston 2 executes its working stroke with a high velocity the sleeve 12 rotates on the ⁵ percussion bar 3, but on the return stroke, executed with a comparatively low velocity, the sleeve 12 retains its position and forces the piston 2 and the percussion bar 3 to rotate. In doing so the tool holder 13 is also rotated ¹⁰ and thus imparts to the drill the required partial rotation. The lower end of the sleeve 12 and the tool holder 13 are surrounded by a casing 16 which carries at its lower end the usual drill cage 17. The cylinder cover 10, the cylinder 1, and the casings 11 and 16 are kept in alignment and resilient contact with one another by lateral bolts 18, between whose nuts 18' and the lateral lugs 16' of the casing 16 helical ¹⁵ springs 18'' are inserted, as indicated by dotted lines in the drawing.

In order to impart to the drill the necessary amount of rotation for the next cutting operation, as explained above, the stroke of ²⁰ the piston 2 and of the percussion bar 3 must attain its full length. This cannot be the case when the compression—which takes place after the cylinder chamber 7, or 8, is exhausted and the piston travels toward the cylinder cover 10, or the casing 11—commences too early, because in such cases the high compression removes the ball-valve 4 too early from its seat. To avoid this I provide short narrow by-pass channels 19 and ²⁵ 20 which I have shown as arranged in the cylinder wall parallel to the axis of the cylinder. Of these by-pass channels the channel 19 is connected by its branches 21 and 22 with the interior of the cylinder, and the channel 20 is similarly connected therewith by means of its branches 23 and 24. Of these branches the branch 22 is placed on a level with a radially disposed exhaust port 25 and the branch 23 is similarly placed on ³⁰ a level with a likewise radially disposed exhaust port 26 in such a manner, that on the return stroke the edge 27 of the piston 2 reaches the branch 22 at the same instant that it reaches the lower edge 28 of the exhaust port 25, whereas on the working stroke the bottom edge 29 of the piston coincides simultaneously with the branch 23 of the by-pass channel 20 and with the upper edge 30 of the exhaust port 26. It is evident that ³⁵ the exhaust ports and by-pass channels may be of any suitable size, shape and number, but the length and the cross sectional area of these channels should be small so as to reduce the amount of air passing there-⁴⁰ through.

The periphery of the piston 2 is provided with annular channels 31 and 32 and when the piston moves in the direction indicated by the arrows, the edge 27 reaches the mouth ⁴⁵ of the branch 22 and the lower edge 28

of the exhaust port 25 simultaneously, as already indicated above. But when the piston travels slightly beyond the position shown in the drawing it fully uncovers the branch 22 and shuts up or entraps spent ⁷⁰ motive fluid of atmospheric pressure in the circular cylinder chamber 7 from which it then escapes through the by-pass channel 19, the annular channel 31 and the exhaust port 25, so that an after-exhaust from the cylinder chamber 7 is assured. This process of after-exhaustion continues without interruption until the mouth of the branch 21 of the by-pass channel 19 is completely overrun by the edge 27 of the piston, at which moment after-exhaust ceases. When the piston 2 moves in the opposite direction the same action as described in connection with the circular cylinder chamber 7 will take place in regard to the annular cylinder chamber 8, because the by-pass channel 20 connects this cylinder chamber with the exhaust port 26 in practically the same way that the by-pass channel 19 connects the cylinder chamber 7 with the exhaust port 25. ⁸⁰

A close examination of the conditions under which the motive fluid is admitted into the cylinder 1, and of the influence the by-pass channels 19 and 20 exert upon them, ⁸⁵ will reveal the fact that the operation of the drill is to a certain extent detrimentally influenced by these by-pass channels, inasmuch as they permit the escape of live motive fluid from the cylinder. This loss of live motive fluid is, however, of little or no account, when the by-pass channels 19 and 20 are of the right length. This is the case when said length does not essentially exceed the distance intervening between the one or the other of the piston faces and the inner shoulder of the adjoining annular piston channel. When for instance the motive fluid is admitted to the annular cylinder chamber 8 while the piston occupies the position shown in the drawing, the piston 2 uncovers on its return stroke the branch 24 of the by-pass channel 20. But since at this moment the branch 23 of this by-pass channel is brought into alignment with the annular channel 32 of the piston it is obvious that some of the live motive fluid destined to retract the piston 2 will escape from the cylinder chamber 8 through the exhaust port 26 during the short interval of time required to let the annular channel 32 pass over the branch 23 of the by-pass channel 20. This time interval is so brief that during this action the reduction of the cylinder pressure is inconsiderable, but this short time interval suffices nevertheless for the after-exhaust ¹⁰⁰ from the cylinder chamber 8 when the piston travels in the opposite direction, i. e. when it is on its working stroke. ¹¹⁰

Since the general operation of the rock drill is thoroughly known in all its phases, ¹²⁰ ¹³⁰

and besides this may be readily understood with the aid of the accompanying drawing, a detailed description of it is deemed superfluous.

5 I claim:—

1. A pneumatic tool comprising a cylinder, a piston slidably mounted therein, means for admitting motive fluid to opposite end spaces of said cylinder so as to be alternately effective upon opposite faces of said piston to reciprocate the same in said cylinder, said piston being provided with two annular, peripheral channels, each located in spaced proximity to the contiguous end of said piston 10
- 15 ton, said cylinder being provided with a pair of exhaust ports in spaced relation to each other and further having by-pass channels each having its two ends terminating at the inner surface of said cylinder for establishing connection between said opposite end spaces of the cylinder, an annular channel of the piston and an exhaust port, the distance between the two ends of each by-pass channel being no greater than the distance 20
- 25 between an end face of the piston and the contiguous annular channel thereof.

2. A pneumatic tool comprising a cylinder, a piston slidably mounted therein, means for admitting motive fluid to opposite end spaces of said cylinder so as to be alternately effective upon opposite faces of said piston to reciprocate the same in said cylinder, said piston being provided with two annular, peripheral channels, each located in spaced proximity to the contiguous end of said piston 30

35 cylinder being provided with a pair of exhaust ports in spaced relation to each other and further having by-pass channels each having its two ends terminating at the inner surface of said cylinder for establishing connection between said opposite end spaces of the cylinder, an annular channel of the piston and an exhaust port, the distance between the two ends of each by-pass channel being approximately equal to the distance between an end face of the piston and the contiguous annular channel thereof. 40
